UNITED STATES PATENT OFFICE

2,636,440

SANITARY PUMP WITH INFINITELY VARIABLE OUTPUT

Gilbert R. Funk, Waukesha, Wis., assignor to
Waukesha Foundry Company, Waukesha, Wis.,
a corporation of Wisconsin

Application July 25, 1949, Serial No. 106,617

4 Claims. (Cl. 103—42)

1

This invention relates to an improved sanitary pump with infinitely variable output.

It is a primary object of the invention to provide a pump of the sanitary type, such as is particularly adapted for pumping milk and the like, with a fully controllable and yet easily cleanable by-pass which, although inadequate to handle the pump output, nevertheless gives full control of such output so that the mere adjustment of spring loading on the by-pass check valve provides infinite control of pump output from zero to full capacity.

Other objects of the invention will appear fully from the following disclosure thereof with particular reference to the accompanying drawings, in which:

Fig. 1 is a view of my improved pump in side elevation, portions thereof being broken away to expose the interior in axial section.

Fig. 2 is a detail view of the end of the pump as it appears in axial section in a plane at right angles to that of Fig. 1.

Fig. 3 is a view of the pump casing and rotors in end elevation, the cover being only fragmentarily illustrated.

Fig. 4 is an interior front elevational view of the cover.

The pump is preferably of the general type illustrated in my Patent 2,279,136 of April 7, 1942. It comprises a casing 5 provided with bearings for a pair of inter-gearied shafts 6 and 7 carrying rotors 8 and 9 with inter-gearied vanes or pistons 10 and 11 respectively. The casing provides passages 12 and 13, one of which is an inlet passage, and the other an outlet passage, depending on the direction of shaft rotation. At the outer ends of the passages, the casing has pipe couplings 14 and 15 respectively. The inner ends of the passages extend into operative proximity to the point where the respective rotors inter-act to displace the liquid pumped.

Detachably connected with the casing 5 to completely expose the pumping chamber when removed, is an end cover 16 held in place by wing nuts 17. In accordance with the present invention, the outwardly extending portion 18 of the cover is provided with a projecting sleeve at 19 having an interior cavity 20 which constitutes a valve chamber. Ducts 21 and 22 bored obliquely in the cover provide communication between the inlet and outlet passages 12, 13 and the bottom of the valve chamber 20.

Seated within the valve chamber and conforming to the bottom and portions of the side wall thereof is a cup-shaped valve element 25 which

2

is desirably made of resiliently flexible material such as natural or synthetic rubber. The bottom of the cup-shaped valve element 25 covers the end of passages 21 and 22 and constitutes a diaphragm valve controlling communication therebetween. The margins of the diaphragm valve are compressed against the bottom of the chamber 20 by a pressure transmitting collar 26 which is forced inwardly by a retaining nut 27 screwed externally to the sleeve portion 19 of the pump casing cover 16. Removal of the retaining nut 27 permits the collar 26 and the valve element 25 to be lifted bodily from the valve chamber 20, thus fully exposing the valve chamber and the passages 21 and 22 for cleaning.

In order to control the regulating action of the diaphragm valve, I provide a plunger 28 having its head 29 seated against the diaphragm which constitutes the bottom of the cup-shaped valve element 25. A spring 30 biases the plunger in a direction to seat the diaphragm valve on the end of the valve chamber and about the mouths of ducts 21 and 22. The outer end of spring 30 engages an adjusting screw 31 which is threaded into the retaining nut 27 and may be held in any desired position by a lock nut 32.

The ducts 21 and 22 and the valve chamber 20 together constitute a by-pass between the high-pressure and low-pressure sides of the pump chamber. Through this by-pass, any desired portion of the pump output can be circulated from the high-pressure side to the low-pressure side of the pump, depending on the pressure with which the diaphragm valve is seated in the valve chamber. Such pressure is readily predetermined by adjusting screw 31 to vary the compression of spring 30.

In actual practice, the capacity of the by-pass system does not need to be comparable to the capacity of the pump in order to effect full control of the pump to deliver any volume from zero to full capacity.

Whatever the reason, the fact is that flow through the pump can be accurately regulated with infinite variation from zero to full pump capacity by simply rotating the pressure-adjusting screw 31 which controls the spring pressure with which the diaphragm valve is seated to regulate flow through the by-pass.

It will be observed that the cup-shaped valve element 25 comprises not only a diaphragm valve, but also packing, whereby no packing which would restrict the freedom of movement of the plunger 28 is necessary. Moreover, from the standpoint of a sanitary pump in particular, it

is noteworthy that the mounting of the adjusting screw 31 in the retaining nut 27, and the guidance of the plunger 28 in such screw, result in an advantageous construction whereby all of these parts are in unitary assembly with the retaining nut. Thus, when the retaining nut is unscrewed, the pressure-adjusting screw 31 comes off with it, and the plunger 28, compression spring 30, pressure transmitting collar 26, and the cup-shaped valve and packing element 25, 10 are all free for removal to expose the chamber and by-pass ducts for cleaning.

I claim:

1. In a sanitary pump of the type having rotors with inter-acting vanes in a pump chamber provided with inlet and outlet passages independently communicating directly with said chamber, the improvement which comprises a removable closure therefor having a by-pass in said closure between said passages, said by-pass comprising ducts leading from said passages to a common valve chamber having a common by-pass valve controlling flow through the by-pass, said by-pass valve comprising a single diaphragm having one face thereof normally closing both said ducts and a biasing spring acting on the by-pass valve in a direction for the seating thereof, the said spring being provided with an exposed pressure-adjusting screw, the adjustment of which regulates flow through the by-pass to control the pump output.

2. In a pump of the type having a pump chamber with inlet and outlet passages and rotors with inter-acting vane pistons operatively mounted in said chamber, said passages being independently directly connected to said chamber, the improvement which comprises the combination of means providing a by-pass including a valve chamber and a pair of ducts leading from the inlet and outlet pump passages to said valve chamber, a cup-shaped valve in the valve chamber having a single face covering the ends of both of said ducts and constituting a diaphragm valve and packing, means anchoring the said valve marginally in said chamber, intermediate portions of said valve being free of said anchoring means for seating and unseating movement respecting said ducts, a plunger having a head portion internally engaged with said valve portions, a spring acting upon said plunger to bias it against the valve portions in a valve seating direction, and an adjustable spring seat for regulating the pressure with which the diaphragm seats to control flow between said ducts.

3. In a pump of the character described, having a pumping chamber and pumping means therein, with high-pressure and low-pressure passages leading from and to said means, the improvement which comprises the combination with means providing a by-pass including a valve chamber having a seat and ducts leading from the respective passages to said valve chamber and opening therein through said seat, of a cup-shaped valve and packing element in said valve chamber having a bottom wall portion constituting a diaphragm valve cooperating with said seat, a collar extending into said valve for forc-

ing its packing portions against said valve chamber, a retaining nut threaded to said valve chamber and in pressure transmitting engagement with the collar, an adjusting screw mounted in said nut and provided with a bore extending toward said seat, a plunger reciprocable in the bore and having a head engaged with the diaphragm portion of the valve and packing element, and a spring confined between the adjusting screw and the plunger and adjustably biased by said screw to urge the diaphragm valve portion of said element to its seat, whereby to regulate flow through said valve chamber between said ducts, the removal of said retaining nut releasing the plunger, spring, collar and element for withdrawal from said valve chamber.

4. In a pump of the character described comprising a casing with a pump chamber and a pair of co-acting pump rotors therein, the said casing providing inlet and outlet passages and including a removable cover having an outwardly extending portion, the combination with such a cover having a valve chamber cavity in its said outwardly extending portion and by-pass ducts leading to the bottom of said cavity from the inlet and outlet passages aforesaid, of a retaining nut threaded to the outwardly extending portion of the cover, a collar extending therefrom into said cavity, a valve and packing element of cup-shaped form having a bottom wall portion constituting a diaphragm valve and a side wall portion fitting interiorly in the cavity and into which said collar extends in pressure engagement subject to the thrust of said nut, a tubular adjusting screw threaded into said nut and adjustable therein axially of the nut, a plunger reciprocably mounted in the screw and provided with a head engaged interiorly with said valve, and a spring encircling the plunger and confined between said head and said screw whereby adjustably to bias said head and valve to a seat in the bottom of said valve chamber cavity, the said spring being of such a length as to be substantially relieved of pressure in one position of the screw to permit substantially free flow through said by-pass ducts and valve chamber from high-pressure to low-pressure sides of the pump chamber, the adjustment of the screw providing infinite variation of pump delivery from zero to substantially full flow according to the pressure imposed on said diaphragm valve, and the said valve, plunger, spring, screw and collar being all removable from the pump chamber upon the mere unscrewing of the retaining nut.
